(57) CLAIM

The ornamental design for an album holder, as shown and described.

DESCRIPTION

FIG. 1 is a front perspective view of an album holder showing the new design wherein the bottom flap is folded; FIG. 2 is a front elevational view of the album holder of FIG. 1;

FIG. 3 is a rear elevational view of the album holder of FIG. 1;

FIG. 4 is a right side plan view of the album holder of FIG. 1;

FIG. 5 a left side plan view of the album holder of FIG. 1; FIG. 6 is a top plan view of the album holder of FIG. 1; FIG. 7 is a bottom plan view of the album holder of FIG. 1; and,

FIG. 8 is a bottom perspective view of the album holder of FIG. 1.

The broken lines are included for the purpose of illustrating portions of the album holder that are not part of the claimed design.

1 Claim, 8 Drawing Sheets
